UNITED STATES PATENT OFFICE.

GEORGE H. GARCELON, OF SWISSVALE, PENNSYLVANIA, ASSIGNOR TO WESTINGHOUSE ELECTRIC AND MANUFACTURING COMPANY, A CORPORATION OF PENNSYLVANIA.

LUBRICATING DEVICE.

1,150,026.

Specification of Letters Patent. Patented Aug. 17, 1915.

Application filed October 14, 1913. Serial No. 735,075.

To all whom it may concern:

Be it known that I, GEORGE H. GARCELON, a citizen of the United States, and a resident of Swissvale, in the county of Allegheny and State of Pennsylvania, have invented a new and useful Improvement in Lubricating Devices, of which the following is a specification.

My invention relates to lubricators and more particularly to lubricators of that type comprising an oil cup located below the bearing and containing a wick for feeding the oil.

As heretofore constructed, difficulty has been experienced on account of the oil wick becoming caught or jammed in the conical opening in the bearing and housing into which the oil cup screws and being thus prevented from coming into contact with the shaft. Another defect in devices of this kind has been the liability of the wick to become bent by the pressure of the spring, so that, after awhile, the wick would not feed properly.

To overcome these objections and also to obviate the necessity for the use of a steady pin, I have devised the present invention. In order that the construction may be clearly understood, reference is had to the accompanying drawing, in which,

Figure 1 is a vertical transverse section through a journal showing an oil cup embodying my improvements applied thereto, parts being in elevation; Fig. 2 is a horizontal section substantially on the line 2-2 of Fig. 1, looking in the direction of the arrow; and, Figs. 3 and 4 are an end view and side view, respectively, of a slightly modified form of wick guide.

Referring to the drawing in detail, 1 designates the usual housing and 2 the bearing, while 3 indicates the shaft. At the under side of the housing 1 is formed a cylindrical boss 1^a, which is internally screw-threaded to receive the threaded upper end of the usual oil cup 8.

The housing 1 is provided, concentrically with the boss 1^a, with a screw-threaded opening 1^b, and the bearing 2 has a similar opening 4 formed therein, the two openings 1^b and 4 being arranged to register, as shown in Fig. 1.

A wick 6, of any suitable or well known material, is located in the oil cup, and is forced upwardly by means of a spring 7,

the upper end of which is wound tightly about the wick and the lower end of which bears against the bottom of the cup 8.

My improvement consists in the provision of a wick guide 5, through which the upper end of the wick projects. This guide is provided with a threaded upper end which is screwed into the aligned threaded openings in the bearing and the housing, and projects downwardly a substantial distance below the top of the oil cup. It will be obvious that this wick guide will prevent the jamming or buckling of the wick and will insure the maintenance of the wick always in the proper position. At the same time, the screw threaded end of the guide acts as a key or steady pin to lock the bearing and housing together so as to prevent rotation or displacement of the former.

The lower end of the wick guide 5 is preferably formed so that it may be engaged by a turning tool. In Figs. 1 and 2, I have shown the guide as formed from a piece of hexagonal bar, bored out to receive the wick. Such a prismatic bar may be readily engaged with a socket wrench, and thus the guide conveniently screwed into the bearing.

In Figs. 3 and 4, I have illustrated the guide 5' as formed of a piece of round tubing, provided at its lower end with notches 9 for the reception of a screw driver or the like. It will, of course, be understood that, in assembling the parts, the bearing is first placed in position in the housing, the wick guide is then screwed into the openings in said parts, the wick is inserted and, finally, the oil cup is screwed into the boss 1^a.

It will thus be seen that I have provided a simple, cheap construction which insures the proper working of the wick at all times, and which obviates the necessity for the use of a separate steady pin or the like.

What I claim is:—

1. The combination with a journal comprising the usual bearing and housing, said bearing and housing having aligned openings, of a wick guide projecting through the opening in the housing and secured in the opening in the bearing, an oil cup carried by said housing, surrounding and concentric with said wick guide, a wick disposed in said cup and passing through said guide, and a spring supported on the bottom of said cup for forcing said wick upwardly.

2. The combination with a journal com-

prising the usual bearing and housing, said bearing and housing having alined openings, of a wick guide projecting through and set into said openings so as to lock said parts together, an oil cup surrounding said wick guide and having its upper end screw-threaded into an opening in said housing concentric with the said alined openings, a wick in said cup having its upper end extending through said guide, and means for forcing said wick upwardly.

3. The combination with a journal comprising the usual bearing and housing, said bearing and housing having alined threaded openings, of an oil cup carried by said housing adjacent said openings, a wick guide located in said cup and screwed into said alined threaded openings, said wick guide having special formations adapted to be engaged by a turning tool, and a wick resiliently supported in said cup and having its upper portion extending through said guide.

4. The combination with a journal comprising a bearing and a housing, said bearing and housing having alined openings, of a wick guide associated with the said openings, an oil cup carried by said housing sur-

rounding and concentric with said wick guide, and a wick resiliently supported in said cup and extending through said guide. 30

5. The combination with a journal comprising a bearing and a housing, said bearing and housing having alined openings, of a wick extending into said openings, means associated with said openings for guiding 35 said wick therein and further means associated with said housing for forcing said wick upwardly.

6. The combination with a journal comprising a bearing and a housing, said bearing and housing having alined openings, of a wick guide associated with the said openings, an oil cup carried by said housing surrounding and concentric with said wick guide, and a wick resiliently supported in 45 said cup and extending through and projecting beyond said guide.

In testimony whereof, I have hereunto subscribed my name this 30th day of Sept. 1913.

GEORGE H. GARCELON.
